UNITED STATES PATENT OFFICE.

CHARLES CRETORS, OF CHICAGO, ILLINOIS.

STEAM-GENERATOR.

No. 923,145.

Specification of Letters Patent.

Patented June 1, 1909.

Application filed May 25, 1908. Serial No. 434,755.

To all whom it may concern:

Be it known that I, CHARLES CRETORS, a citizen of the United States of America, and a resident of Chicago, in the county of Cook 5 and State of Illinois, have invented certain new and useful Improvements in Steam-Generators, of which the following is a specification.

This invention relates to steam generators 10 and the like, and of the coiled water tube type, and has for its object to provide a simple, durable and economical structural formation and combination of parts whereby a very large heating surface within a defined 15 area is attained, all as will hereinafter more fully appear.

In the accompanying drawings: Figure 1, is a side elevation illustrating the general arrangement of parts and with a series of four 20 coils of heating tubes in place. Fig. 2, is a plan view with one coil of the heating tubes in place. Fig. 3, is a detail horizontal section on line $x-x$ Fig. 1 of one of the annular terminal heads or manifolds. Figs. 4 and 5 25 are companion detail sections on line $x'-x'$ Fig. 2, illustrating the intermediate connection between an upper and lower unit of the apparatus.

Similar numerals of reference indicate like 30 parts in the several views.

Referring to the drawings, 1 represents a series of annular terminal heads or manifolds, and 2 an intermediate cylindrical shell arranged between a pair of said heads to impose 35 separated relation thereon to receive the ends of the series of coiled heating tubes hereinafter described. And as so arranged the parts described will constitute a complete steam generating unit, of which a number 40 can be assembled together to afford a generator of the required power of capacity. In Fig. 1 of the drawings two of such units are shown connected together to form the generator.

45 3 are the series of heating tubes secured at their respective upper and lower ends to a pair of the terminal heads 1 in the manner and by means hereinafter set forth. In the present construction each tube of the series 50 will have a main spiral form and arrangement between the respective upper and lower terminal heads aforesaid, and each

tube is in turn formed by a series of circular loops 4 to afford a very extensive heating surface in a given space in the annular fire 55 chamber in which they will be arranged in actual use.

At each end each coiled heating tube will have extensions 5 and 6, that are approximately radial to the axis of the annular terminal heads aforesaid when attached thereto.

When assembled to form a complete generator unit, the series of loops 4 aforesaid will lie closely together one above the other with each individual loop staggered or in vertical 65 mis-alinement with the adjacent loop of its own tube and with the adjacent loops of the next adjacent heating tubes, as illustrated in Fig. 1.

The manufacture of the special form of 70 tube above described is readily and economically attained by first winding a section of tubing spirally upon a mandrel of the required diameter, after which the individual loops of the winding so formed are spread 75 apart laterally to produce the main spiral or twist of the tube above described.

It is within the scope of the present invention to employ the present special form 80 of heating tubes in connection with a central drum or boiler in lieu of the special form of tubes shown in my former patent No. 728,548, dated May 19, 1903; in my preferred construction however the following arrangement of parts will be employed.

7 are a series of return or U shaped passages formed in the terminal heads aforesaid. Each of said passages has its end portions arranged radial to the axis or center 90 of the terminal head and formed with screw-threaded counter bores and abutment shoulders 8, for the convenient attachment of the heating tubes as hereinafter described.

9' and 10 10' are inlet and outlet necks, respectively, arranged in adjacent relation 95 on the uppermost terminal head of each generator unit aforesaid. Such necks are formed with ell shaped passages, which like the passages 7 above described, are formed with screw-threaded counter bores and inner abutment shoulders 8' as shown in Figs. 4 and 5. One end of the passage in an inlet neck 9 or 9' has connection with the first of the series of heating tubes of a gen-

erator unit, while the other end of such passage has connection with the water supply pipe 11 as indicated in Figs. 1 and 2. In like manner the passage in the outlet neck 5 10 or 10' has at one end connection with the last of the series of heating tubes of a generator unit, while at the other end said passage has connection with the steam supply pipe 12 from the generator.

- 10 Where two units are employed to form the generator, an example of which is used in the present drawings to illustrate the invention, the water supply pipe 11 will be connected to the inlet neck 9 of the upper 15 terminal head of the upper unit, and the steam supply pipe 12 to the outlet neck 10' of the upper terminal head of the lower unit. And in connection with such arrangement of parts, the outlet neck 10 of the upper 20 per terminal head of the upper unit will be connected to the inlet neck 9' of the upper terminal head of the lower unit by a goose neck tubular connection 13, as shown in Figs. 1 and 2.
- 25 By the described construction a single continuous heating passage is provided for the generation of the steam, such passage embracing the entire series of heating tubes 3 and return passages 7 by which the said 30 tubes are connected in series.

14 are a series of screw-threaded nipples fitted over the attaching extensions 5 and 6 of the heating tubes and screwing into the aforesaid screw-threaded counterbores of 35 the passages 7 in the terminal heads.

15 are rims or flanges on the ends of the attaching extensions 5 and 6 of the heating tubes, and against which the nipples 14 have bearing to force said flanges against the 40 abutment shoulders 8, before described, and provide a substantial and steam tight attachment of the heating tubes in place.

The goose neck tubular connection 13, as well as the water and steam pipes 11 and 12, 45 will be secured in a like manner and by similar means to the inlet and outlet necks 9 9' and 10 10' of the terminal heads.

While the present invention is shown and described as applied to a steam generator, 50 it is evident that the same can be applied with equal advantage to steam or other condensers, radiators and the like, and the scope of the present invention is accordingly intended to embrace such applications of the 55 present improved construction and arrangement of parts.

Having thus fully described my said invention what I claim as new and desire to secure by Letters Patent, is:—

- 60 1. In a steam generator or like appliance, the combination of an upper terminal head, a lower terminal head, and a series of tubes connected at top and bottom to said heads,

each tube consisting of a series of circular loops arranged in lateral misalignment to 65 each other to impart a spiral form to the tube as a whole, the terminal heads having a series of U shaped passages connecting adjacent pairs of the heating tubes together, substantially as set forth.

2. In a steam generator or like appliance, the combination of an upper terminal head, a lower terminal head, and a series of tubes connected at top and bottom to said heads, each tube consisting of a series of circular 75 loops arranged in lateral misalignment to each other and in like misalignment and in overlapping relation to the loops of the next adjacent tubes, the terminal heads having a series of U shaped passages connecting adjacent pairs of heating tubes together, substantially as set forth.

3. In a steam generator or like appliance, the combination of a pair of annular terminal heads formed with radial attaching 85 bores, a series of tubes having radial extensions connected to said bores, each tube consisting of a series of circular loops arranged in lateral misalignment to each other to impart a spiral form to the tube as a whole, 90 necks arranged on the inner sides of the annular terminal heads, and inlet and outlet pipes connected to said necks, substantially as set forth.

4. In a steam generator or like appliance, 95 the combination of a pair of annular terminal heads formed with radial attaching bores, a series of tubes having radial extensions connected to said bores, each tube consisting of a series of circular loops arranged 100 in lateral misalignment to each other and in like misalignment and in overlapping relation to the loops of the next adjacent tubes, necks arranged on the inner sides of the annular terminal heads, and inlet and outlet 105 pipes connected to said necks, substantially as set forth.

5. In a steam generator or like appliance, the combination of an upper terminal head formed with inlet and outlet passages in adjacent relation and with a series of U shaped 110 passages adapted to connect adjacent pairs of heating tubes together, a lower terminal head having a series of U shaped passages adapted to connect adjacent pairs of heating tubes together, and a series of heating tubes connected at top and bottom to said heads, each tube consisting of a series of circular loops arranged in lateral misalignment to each other to impart a spiral form to the 115 tube as a whole, substantially as set forth.

6. In a steam generator or like appliance, the combination of an upper terminal head formed with inlet and outlet passages in adjacent relation and with a series of U shaped 120 passages adapted to connect adjacent pairs 125

of heating tubes together, a lower terminal head having a series of **U** shaped passages adapted to connect adjacent pairs of heating tubes together, and a series of heating tubes connected at top and bottom to said heads, each tube consisting of a series of circular loops arranged in lateral misalignment to each other and in like misalignment and in

overlapping relation to the loops of the next adjacent tubes, substantially as set forth. 10

Signed at Chicago, Illinois, the 20th day of May, 1908.
